DISHWASHER

Harry Geller, Louisville, Ky., assignor to General Electric Company, a corporation of New York

Filed May 26, 1958, Ser. No. 737,648

3 Claims. (Cl. 239—220)

This invention relates to dishwashers, and more particularly to a machine of this character having improved means for impelling or spraying water within the washing chamber.

A general object of this invention is to provide a dishwasher including improved means for circulating high velocity streams of water throughout the washing chamber of the dishwasher.

Another object of the invention is to provide a dishwasher having improved means for spraying high velocity rotating sheets of water within the washing chamber of the dishwasher.

Further objects and advantages of this invention will become apparent as the following description proceeds, and the features of novelty which characterize the invention will be pointed out with particularity in the claims annexed to and forming a part of this specification.

Briefly stated, in accordance with one aspect of this invention there is provided a dishwasher including a rotary impeller surrounded by a freely rotatable cylindrical baffle having an elongated opening therein through which a sheet of water is discharged when the impeller is rotating, it being understood that the baffle is arranged to admit water at the rate at which it is discharged. Rotation of the impeller causes rotary movement of the body of water within the baffle, and this in turn induces relatively slow rotary movement of the baffle so that the sheet of water discharged therefrom moves in a rotating pattern, so that there is, in effect, a water coupling connecting the impeller and the baffle.

For a better understanding of this invention reference may be made to the following description and the accompanying drawing in which:

Fig. 1 is an elevation view, partially in section, of a dishwasher embodying the present invention.

Fig. 2 is a fragmentary cross sectional view taken along the line 2—2 in Fig. 1, some of the parts being broken away.

Referring to the drawing, the dishwasher illustrated therein includes a washing chamber 1 defined by a top wall 2, a rear wall 3, side walls 4 and 5 and a generally concave bottom wall 6. Thus washing chamber 1 is generally rectangular in configuration, and includes a front opening provided with a peripheral sealing gasket 7 and a door 8 which is hinged or otherwise secured to the dishwasher frame so as to permit access through the door opening to chamber 1. Bottom wall 6 forms a sump in which the water impeller means of the present invention is located.

A dish holding rack 9 is arranged to be supported within washing chamber 1, and as illustrated in Fig. 1 the rack may be constructed so as to rest on bottom wall 6 and to support a number of dishes in the positions indicated by broken lines. Preferably, rack 9 is so arranged that the dishes are supported in such a way that their inner or top surfaces are directly exposed to streams of water impelled upwardly from the sump at the bottom of the washing chamber.

2

Mounted in the sump formed by the configuration of bottom wall 6 is an elongated impeller 10 which, as shown in Fig. 1 is generally S-shaped in cross section. Impeller 10 is supported for rotation on a horizontal axis generally parallel to the longitudinal axis of the sump by means of end shafts 11 and 12 which are fixedly secured to the ends of the impeller and are arranged to rotate in suitable bearings secured in side walls 4 and 5 of the washing chamber. Thus, as shown in Fig. 2, shaft 11 is supported in bearing 13 which is secured to side wall 5, and it will be understood that shaft 12 is supported in a similar manner. Secured to the end of shaft 11 is a pulley 14 which cooperates with pulley 15 secured to the shaft of motor 16 and belt 17 to form a drive system for rotating impeller 10. Motor 16 is mounted in a compartment below washing chamber 1 which is formed by a front wall 18, a rear wall 3, bottom wall 19 and side walls 20 and 21.

In accordance with the present invention, impeller 10 is surrounded by an elongated cylindrical baffle 22 freely mounted for rotation about the rotary axis of the impeller. Thus the end portions of baffle 22 may be formed as illustrated in Fig. 2, so as to include an annular end wall 23 and a sleeve portion 24 arranged to engage the outer surface of bearing 13. Baffle 22 is provided with a pair of diametrically opposing axially aligned openings 25 and 26 which preferably extend along the entire length of the baffle. As will presently be described, openings 25 and 26 alternately function as entrance openings for admitting water to the area swept by impeller 10 and exit openings through which water is expelled from the baffle into the washing chamber.

Water for washing operations may be supplied to washing chamber 1 by any suitable means such as a water inlet valve 27 connected in a water supply line 28 which supplies water to an inlet nozzle 29. Similarly, suitable means for discharging water from washing chamber 1 are provided such as a drain pipe 30 connected to the bottom of the sump formed by bottom wall 6 and also to a drain valve 31. It will be understood that impeller 10 and baffle 22 are arranged to operate partially submerged in water as indicated by the water level shown in Fig. 1.

In operation, after the dishes or other articles to be washed have been placed on rack 9 and door 8 moved to its closed position, water is admitted to washing chamber 1 through inlet nozzle 29 so as to supply sufficient water to the chamber to partially submerge rotary baffle 22. Motor 16 is then energized and by means of pulleys 14 and 15 and belt 17 drives impeller 10 at a relatively high speed (1700 r.p.m., for example) in the direction indicated by the arrow in Fig. 1. Rotation of the impeller 10 causes rotary movement of the water in the zone swept by the impeller, and the resulting movement of the water induces relatively slow rotation of baffle 22, it being understood that the rapidly rotating mass of water therein produces sufficient frictional force along the inner surface of the baffle to cause rotation thereof. This effect may be described as a water coupling connecting the impeller and the baffle as distinguished from separate drive motors and link or gear drives mechanically connecting the impeller to the baffle. At the same time water within the baffle is expelled through either opening 25 or opening 26, depending upon which opening is above the water level. The opposite opening in baffle 22 which is below the water level functions as an inlet opening through which water is admitted to the zone swept by impeller 10. In practice, it has been found that a high velocity sheet of water is discharged through the uppermost opening in baffle 22 and that this sheet of water sweeps or rotates across the upper space within the washing chamber so that the articles supported

on rack 9 are subjected to a constantly moving stream of water.

While I have shown and described a particular embodiment of my invention, I do not desire the invention to be limited to the particular construction disclosed, and I intend by the appended claims to cover all modifications within the true spirit and scope of my invention.

What I claim is:

1. In a dishwashing machine comprising a washing chamber, an elongated impeller adapted to be partially submerged in water in said chamber, means for rotating said impeller, and a cylindrical baffle surrounding said impeller, said baffle having inlet openings that are positioned below the water level for admitting water into the zone swept by said impeller and outlet openings above the water level through which water is expelled during rotation of said impeller, said baffle being freely mounted for rotation about the rotary axis of said impeller, whereby rotary movement of water within said baffle induced by rotation of said impeller causes continuous rotation of said baffle at a speed substantially lower than the speed of rotation of said impeller so that there is in effect a water coupling connecting the impeller and the baffle, the baffle rotating in the water causing the openings to alternately pass through the water in the chamber, the opening above the water serving as an outlet opening while the opening below the water serves as an inlet opening, both the inlet and outlet openings extending for substantially the entire length of the baffle.

2. In a dishwashing machine comprising a washing chamber including a concave bottom wall forming a sump, an elongated rotary impeller mounted in said chamber for rotation partially submerged in water about an axis parallel to the longitudinal axis of said sump, means for rotating said impeller, and an elongated cylindrical baffle surrounding said impeller, said baffle having a pair of diametrically opposed openings therein which extend for substantially the entire length of the baffle, said baffle

being freely mounted for rotation about the rotary axis of said impeller, whereby rotation of said impeller causes the water to drive the baffle in the same direction as the impeller but at a relatively slow rate and it also discharges a moving stream of water from one of said openings which is above the water while the other opening is under water.

3. In a dishwashing machine comprising a washing chamber including a concave bottom wall member defining a sump, an elongated impeller mounted in said sump for rotation partially submerged in water on a horizontal axis generally parallel to the longitudinal axis of said sump, means for rotating said impeller, an elongated cylindrical baffle surrounding said impeller, said baffle having a pair of diametrically opposing axially aligned openings therein which extend for substantially the entire length of the baffle, each of said openings being defined by a first axially aligned edge portion of said baffle and a second axially aligned edge portion of said baffle, said first and second edge portions being swept by said impeller in the order just named, each of said first edge portions being bent outwardly from the cylindrical surface of said baffle, said baffle being freely mounted for rotation about the rotary axis of said impeller, whereby rotary movement of water within said baffle induced by rotation of said impeller causes continuous rotation of said baffle at a speed substantially lower than the speed of rotation of said impeller and said impeller discharges a continuously moving sheet of water from one of said openings as it moves through an arc above the water level in said sump.
